MOUTH PROTECTOR

Clarence F. Coleman, Mishawaka, Ind.

Application February 18, 1952, Serial No. 272,048

4 Claims. (Cl. 128—136)

1

This invention relates to an improved construction for a mouth protector and tooth guard adapted to be worn by football players, boxers, hockey players and others athletes who are likely to sustain injury to their teeth and mouth.

Devices of this nature have been available for some time, but to my knowledge none has been completely satisfactory. Among the objections were that they fitted poorly, presented an unsightly appearance, were bulky in the mouth, and failed to remain in place when the mouth was open, or under severe jolts and shocks.

A primary object of my invention is to offer good protection to the lips to prevent their being cut by the teeth, and to prevent the teeth from being broken or chipped by clashing together under impacts. Another object is to obviate the aforementioned objections by providing a tooth guard that is comfortable to wear, does not interfere with breathing, and which does not make the wearer look unnatural. Another object of my invention is to produce an improved guard construction which, in addition to the foregoing advantages, will remain securely in place whether the mouth is open or closed. It is generally true that before impact an athlete will close his mouth tightly, but football players for example, often run hard with their mouths open to facilitate breathing, and it is essential that the guard remain in place under such circumstances. These and other objects will become apparent from the following specification when read in conjunction with the drawings in which:

Fig. 1 is a top view of my improved tooth guard construction, looking into the tooth cavities.

Fig. 2 is a side view of my improved tooth guard construction.

Fig. 3 is a bottom view of the guard showing the indentations into which the occlusals of the lower teeth fit.

Fig. 4 is a side view, partially in cross-section, of the guard in position in the mouth of the wearer.

Fig. 5 is a cross-sectional view taken along the line 5—5 of Fig. 1.

The tooth guard constituting my invention comprises a soft rubber-like plastic shell and an integral rigid arcuate palatal piece adapted snugly to encase the upper teeth. The integral palatal piece imparts rigidity to the soft, resilient shell so that it will lock into the upper jaw. I find that by completely encasing the upper teeth with my protector adequate protection is also provided for the lower teeth. I have provided indentations corresponding to the impression of the cusps of

2

the lower teeth in the undersurface of the occlusal covering portion of the shell; thus when the mouth snaps shut due to impact, the occlusals of the lower teeth find lodgement in the impressions, which cushions them against the blow. The upper front teeth naturally project beyond the lower teeth and by providing a cushion over the outer and occlusal surfaces of the uppers, the lowers are automatically protected.

10 Referring to the drawings, the guard comprises a resilient arcuate-shaped shell designated at 9 and a rigid arcuate palatal piece 10 integral therewith. The shell 9 is adapted to encase the upper teeth as shown in Fig. 4 with the front portion 6 of the shell against the outer surface of the teeth, the bottom portion 7 over the occlusals of the teeth, and the rear portion 8 against the inner surface of the teeth. The shell is cast against a model of the teeth so that it will fit accurately. 15 It is my intention that the protectors be made up separately for each individual wearer, conforming to the impression of his teeth.

20 The rigid palatal piece 10 lies generally between the rear portion 8 of the shell and the inner-face 25 of the gums and palate, but does not cover the inner surfaces of the teeth. The piece 10 is arcuate-shaped like the shell and has a marginal portion 11 extending upwardly from the lower boundary of the gums over the palate, covering the margin thereof. The remainder of the palate beyond the marginal area is uncovered, so the tongue is normally not in contact with the palatal piece. Extending downwardly from the marginal portion 11 are a series of triangular-shaped fingers 12 that project down into the crevices between the teeth and, through extension wires 14, connect with a band 13 embedded beneath the surface of the plastic shell. This is most clearly illustrated in Fig. 5. The piece 10, including marginal portion 11 and the fingers 12, is preferably 30 cast in one piece so that it conforms accurately to the mouth. It will be noted that although the palatal piece is contiguous to the inner surfaces of the teeth, it covers only the margin of the 35 palate and the gums surrounding the teeth. The inner surfaces of the teeth lie below the marginal portion 11 and between the fingers 12, and most of the area thereof is in contact with the rear portion 8 of the plastic shell.

40 The palatal piece is anchored to the shell by a narrow metal band or wire 13 which is embedded beneath the surface of the resilient shell. The distance of the band below the surface may vary, but I prefer a distance of from $\frac{1}{2}$ " to $\frac{1}{8}$ ". This 45 is adequate to prevent the rigid band from being

noticeable to the wearer since there is sufficient soft resilient material between the teeth and the band to provide a cushion therebetween. The band is also arcuate in shape and follows a line which runs anteriorly from between the cusps of the bicuspid and molar teeth, around behind, not under, the incisor and canine teeth. Elevationally this line roughly follows the contour of the occlusals of the lower teeth when the mouth is closed. The band 13 is connected to the tips of the fingers 12. Where the fingers terminate short of the surface of the shell, short wires 14, shown in Fig. 5, are employed to connect the band 13 to the tips of the fingers. One end of wire 14 is soldered to the tip 12 and the opposite end is soldered to band 13. Both the band 13 and the wires 14 are completely enclosed in the shell 9. The posterior sections of the band are embedded in the occlusal covering portion 7 and the anterior section of the band which lies behind the incisor and canine teeth is embedded in the rear portion 8 of the shell 9. In this way the palatal piece 10 is integrally secured to the shell to produce a unitary structure. Although I prefer that the posterior sections of the band lie in the occlusal covering portion 7 of the shell, it is apparent that the band may be embedded in the rear shell portion 8, posteriorly as well as anteriorly.

It will be understood that the shell need not completely cover the inner surfaces of the teeth. It is essential only that the outer surfaces and the occlusal surfaces be completely cushioned. The palatal piece contiguous to the inner surfaces of the teeth is sufficient to hold the guard in place. In such a construction, the metal band to which the palatal piece is anchored lies in the occlusal covering portion 7 of the shell along its entire length.

It is desirable to form the impression of the occlusals of the lower teeth in the under surface of shell portion 7 as indicated at 15 in Fig. 3. Thus, when the mouth is closed the cusps of the lower teeth lock into the guard to hold it securely in place. The impression 15 also permits the mouth to close naturally and prevents undue pressure on the teeth because of an uneven cutting surface.

The palatal piece need not extend rearwardly to the extremities of the shell. It is necessary only that the piece extend past the bicuspids to the first molars. A palatal piece of this size is sufficient to hold the protector firmly in the wearer's mouth. The number of teeth covered by the shell is also variable. Obviously the teeth farther back in the mouth are less likely to be injured or to cause injury to the mouth than those toward the front. Usually I prefer to make the guard long enough to cover the first and second molars on each side.

The plastic shell is preferably made from a transparent rubber-like thermoplastic resin such as polyethyl acrylate or other polyacrylate resins known in the dental trade. Polyethylene or plasticized polyvinyl chloride are also suitable. These materials will soften at elevated temperatures so that they can be shaped precisely to the mouth of the wearer. Rubber may be used, but it requires vulcanization and has a disagreeable taste which the resins do not. The resins offer the additional advantages of being resistant to chemicals in the mouth, and above all, of being transparent. Consequently, a shell made from these materials permits the wearer's teeth to show

through, providing a natural appearance. The thickness of the shell is not critical and will vary slightly in different portions. I prefer to make it from $\frac{1}{8}$ " to $\frac{1}{4}$ " thick. This thickness is sufficient to absorb jolts that accompany blows to the mouth without being too bulky.

The palatal piece is preferably made from metal such as "white metal" commonly used in the art for constructing bridge work, etc. This metal can be cast to shape making it desirable for use in my tooth protector. Of course, it is not essential that metal be used, for any rigid material that can be shaped and which will meet the other obvious requirements will do.

15 It may be seen from the foregoing description that the palatal piece, being rigid and conforming precisely to the mouth and to the contours of the teeth, is well adapted to hold the soft and relatively flimsy teeth-encasing shell firmly in position, whether the mouth is opened or closed.

I claim:

1. A protector for teeth comprising a transparent rubber-like shell adapted to conform to and encase the upper teeth and an arcuate metal palatal piece integral therewith, said palatal piece adapted to extend upwardly over the margin of the palate contiguous to the inner surfaces of the teeth and having pointed fingers adapted to fill the spaces between said surfaces, said fingers 25 being secured to an arcuate metal band the posterior sections of which lie embedded in the occlusal-covering portion of said shell and the anterior section of which lies embedded in the portion of the shell covering the inner surface 30 of said teeth.

2. A protector for teeth comprising a transparent rubber-like shell adapted to conform to and encase the upper teeth and an arcuate metal palatal piece integral therewith, said palatal piece 40 adapted to extend upwardly over the margin of the palate contiguous to the inner surfaces of the teeth and having pointed fingers adapted to fill the spaces between said surfaces, extension wires connecting each of said fingers to an arcuate metal band embedded in the occlusal-covering 45 portions of said shell.

3. A protector for teeth comprising a resilient shell adapted to encase the outer surfaces and occlusals of the upper teeth, and an arcuate rigid palatal piece integral therewith, said palatal piece 50 adapted to extend upwardly over the margin of the palate contiguous to the teeth, and having downwardly extending fingers secured to a relatively inflexible band embedded in the occlusal-covering portions of said shell.

4. A protector for teeth comprising a resilient shell adapted to conform to and encase the upper teeth, and an arcuate rigid palatal piece integral therewith, said palatal piece adapted to extend 60 upwardly over the margin of the palate contiguous to the teeth, and having downwardly extending fingers secured to a relatively inflexible band embedded in said shell.
